UNITED STATES PATENT OFFICE.

JOHN H. G. ZUNNER, OF ROCHESTER, NEW YORK.

PROCESS FOR USE IN PITCHING BARRELS.

No. 892,108.

Specification of Letters Patent.

Patented June 30, 1908.

Original application filed October 15, 1906, Serial No. 339,051. Divided and this application filed June 11, 1907.
Serial No. 378,418.

To all whom it may concern:

Be it known that I, JOHN H. G. ZUNNER, a citizen of the United States, residing at Rochester, New York, have invented certain new and useful Improvements in Processes for Use in Pitching Barrels; and I do hereby declare the following to be a full, clear, and exact description of the invention, such as will enable others skilled in the art to which it appertains to make and use the same.

My invention relates to improvements in processes for use in pitching barrels and like vessels.

In the processes of pitching or coating the interiors of barrels hitherto employed, the pitch is first heated to about 400° or 425° F., and then supplied to the interior of the barrel in any suitable way, as for example, by spraying it or pouring it into the barrel, after which the barrel may be agitated or moved about either by hand or by suitable machinery in order to bring the pitch into contact with all portions of the inner surface of the barrel. Where however, the pitch is thoroughly sprayed into the barrel by a suitable apparatus, the agitation of the barrel for the purpose of distributing the pitch evenly may be dispensed with.

The pitch having been applied, it is usual to employ some step for cooling the pitch as rapidly as possible. This has been done heretofore either by continuing the agitation of the barrel, as by rolling it by hand or by machinery, or by blowing compressed air into the barrel, and allowing said air to escape therefrom. Owing to the fact that the pitch is confined within the barrel, which is of wood and a poor conductor of heat, the pitch cools but slowly by mere rolling or other agitation, and during this time the vapors or pitch smoke condense on the interior walls of the barrel and within the coating, thus contaminating the latter to such an extent that it is generally considered necessary to fill the barrels with water after they are coated in order to wash out the condensed products of the smoke or vapors, and even this treatment is not always successful in removing all contaminations.

When compressed air is injected into the barrel immediately after the pitch coating has been applied, it not only does not satisfactorily remove the pitch smoke, but in some cases even aggravates the difficulty by causing the pitch vapors to condense more

rapidly. The explanation of this is probably that the use of compressed air raises the pressure of the gases, vapors and air within the barrel and thereby correspondingly raises the temperature of volatilization of said pitch vapors, whereby a condensation takes place. Whether this be the true explanation or not, I have discovered that if instead of employing air at a pressure above atmospheric and thereby causing an over-pressure in the barrel, I cause a rarefaction of the atmosphere within the barrel, that is to say, reduce the pressure, as for example, by exhausting the gaseous contents of the barrel, I not only remove the heated vapors and air from the barrel and thereby assist in the rapid cooling of the barrel, but also I prevent the said pitch vapors from condensing in the barrel, probably for the reason that the reduction of pressure within the barrel lowers the temperature of volatilization of said vapors, so that they remain volatile and are thereby exhausted, while any vapors already condensed may volatilize at the temperature of the coating and be exhausted from the barrel. Furthermore, the act of exhausting the gaseous contents of the barrel to create the desired vacuum or reduction of pressure in the barrel not only draws off the pitch vapors and heated gases and air, but also in itself produces a rapid cooling of the coating, since any reduction of pressure of the gas is itself accompanied by a reduction of temperature.

A further important advantage of my new process is that it enables the barrels to be tested rapidly and with more certainty to determine whether or not they leak than when using compressed air, because in the latter case, the pitch may be pressed outward and temporarily close a leak in the barrel, so that the gage would indicate that the barrel was tight, whereas with a reduction of pressure within the barrel as in my process, the outside air acting through a leaky place in the barrel will push inward the soft pitch coating and thereby cause the gage pressure to rise, indicating instantly the imperfection of the barrel, thus giving an opportunity to remedy the defect at once.

In order to carry out the process, any suitable exhausting means may be employed, for producing the desired vacuum in the barrels, as for example, the new apparatus herein-after described, which, however, forms no

part of the present invention but which is described and claimed in my application Serial No. 339051, filed October 15, 1906, of which this application is a division. This 5 apparatus, which is referred to only as one example of the means which may be employed for carrying out my improved process, is shown in the accompanying drawings, in which

10 Figure 1 is a side elevation of the device connected to a barrel, the latter being shown in section; and Fig. 2 is a central sectional view of the operating head of this device.

Referring to the drawings, A is a head provided with means for engagement with the 15 barrel B or other vessel, said means consisting in the present case of a flanged or extended shoulder a from which projects a tube a' arranged to extend a distance into the vessel, this tube in the device shown being closed at one end and provided with a series 20 of perforations. The tube a' is made of such a diameter that it may be conveniently inserted in the opening in the vessel, as for example, into the bung hole of the barrel, as 25 shown in Fig. 1. The shoulder or flange a , however, is larger than this opening or bung hole and between it and the outside of the vessel is placed a packing device, a^2 , as for 30 example, a gasket of rubber or other suitable elastic material, which in the present case is shown as partly received in a recess in the shoulder a as indicated by the dotted lines in Fig. 1. The head A is hollow, and has a discharge outlet, as indicated at a^3 provided 35 with means for closing it and for opening it quickly, such means consisting in the present example of a gate valve a^4 operated by its handle a^5 .

40 Suitable means is provided for creating a suction in the head A so that the vapors and smoke may be drawn from the vessel and discharged through the discharge outlet a^3 . This suction creating means connected with the head A, consists, in the present example, 45 of a jet device and more particularly of a jet device arranged to operate with compressed air. In the embodiment of my invention shown in the drawings, this jet device consists of a jet tube C arranged to discharge upward or in a direction away from the barrel B and toward the discharge outlet a^3 . The jet tube C is provided with fluid under pressure from any suitable source, as for example, by 50 means of a flexible conductor such as the hose C' which is connected with the jet tube C by means of a pipe C² passing through the wall of the head A. The hose C' is intended to be supplied with fluid under pressure, as 55 for example, compressed air from any suitable source not shown. A valve C³ is placed at any convenient point in order to control the supply of air or the like to the jet tube.

To the head A is connected a gage D by 60 which the pressure or vacuum in the head A

may be ascertained. Between the gage D and the head A is placed a cock D' whereby the communication between the head and the gage may be cut off. The head A is mounted in such a manner that it may be firmly 70 pressed against the barrel or other vessel and removed therefrom. In the example shown, the head A is mounted on the end of a bar E longitudinally movable in a frame work F, the bar E being provided with suitable mechanisms for moving it longitudinally, as for example, by supplying the bar E with a rack E' engaged by a toothed segment G mounted on a lever G' fulcrumed at G' upon the frame work, the free end of the lever G' serving as 75 an operating handle.

The frame-work F of the apparatus, in the preferred embodiment of my invention, comprises a base F' upon which the barrel B may be mounted upon suitable chock-blocks as 80 indicated at F².

The tap-hole of the barrel B is shown at b.

In carrying out my process the barrel is provided with an interior coating of pitch in any suitable way, as, for example, by pouring or spraying melted pitch into it at a temperature of about 400 to 425° Fahr. through the bung hole, the tap-hole being plugged. The barrel is agitated, if necessary, to bring the hot pitch into contact with every part of the inside of the barrel, as is usual and well known to those skilled in the art. As quickly as possible thereafter, while the coating is still hot and before it has lost any appreciable amount of its heat, the barrel is placed 90 upon the blocks F² with its bung hole upward, the head A at this time being elevated 95 so as to be out of the way, by pulling down the lever G'. Thereupon the head A is rapidly depressed, either by releasing the lever 100 G' and allowing it to descend by its own weight, or by pushing upward upon the said lever G' to hasten its movement. When the head A is depressed the tube a' enters the bung hole of the barrel and the packing device a² comes into contact with the outside 110 of the barrel. By pressing upward on the lever G' the said packing device a² is firmly compressed between the shoulder a and the barrel, thus making an air-tight or substantially air-tight connection between the head and barrel. The means for creating a vacuum 115 is then put in operation to exhaust the gaseous contents of the barrel and thereby produce a reduction of the pressure in the 120 barrel.

In the use of the apparatus hereinbefore described this is accomplished by opening the valve C³ and allowing the compressed air to enter the jet-tube, while at the same time 125 opening the discharge outlet a^3 by opening the gate valve a^4 . The escape of the compressed air upward through the jet tube C and outward through the discharge outlet a^3 causes a suction on the well known principle 130

of an injector and thus exhausts the vapors, smoke and heated air from the interior of the barrel and discharges the same through the discharge outlet a^3 , whereby the pressure in the barrel is reduced. At this time the barrel may be tested to determine whether or not it is leaky simply by momentarily shutting the valve C^3 and watching the gage D , whereupon the valve C^3 is again opened. The rapid reduction of pressure in the barrel due to the exhaustion of the gaseous contents causes a drop in temperature which quickly cools the coating in the barrel. This cooling of the barrel is assisted by allowing the cooler air from the outside to enter through the tap-hole. As the area of this tap-hole, however, is very restricted compared with the discharge capacity of the jet device, the restricted tap-hole acts as an expansion valve, and the incoming air expands as it enters the barrel, thus absorbing more heat. The continued action of the jet device causes a flow of the cooler air from the outside into the barrel through the tap-hole and outward through the discharge outlet so that in this way the said air is continuously removed as rapidly as it becomes warmed by the heat which it abstracts from the coating.

When the treatment of the barrel is completed, the valve C^3 may be closed, the lever G' pulled down to lift the head A and its tube a' clear of the barrel, and the barrel removed, whereupon the apparatus is ready to receive the next barrel to be treated. The gage D may be put in communication with the head A at any time by opening the cock D' , in order to measure the vacuum which is being produced by the jet device.

My improved apparatus has an additional feature which adds to its value, as will now be explained. Some of the experts in this art prefer to submit the interior of the barrel to a pressure such as the pressure of compressed air after the pitch coating is in place and before the same has been entirely hardened. With my apparatus, this can be done at any time desired, by merely closing the

gate-valve a^4 and the tap-hole b of the barrel, whereupon the jet device ceases to function as an injector and the compressed air is confined in the head A and barrel B until the pressure in the latter is equal to that of the supply of compressed air. The gage D serves to indicate and thus allow the control of this pressure.

Having thus fully described my invention, what I claim as new and desire to secure by Letters Patent, is:

1. The process of pitching barrels and the like, which consists in supplying them with an inner coating of melted pitch, and then exhausting the gaseous contents of the barrels.

2. The process of pitching barrels and the like, which consists in supplying them with an inner coating of melted pitch, then removing the heated gaseous contents of the barrels and admitting air to the interior of said barrels.

3. The process of pitching barrels and the like, which consists in supplying them with an inner coating of melted pitch, then exhausting the heated gaseous contents of the barrels, admitting air to the interior of the barrels and allowing said air to expand within the interior of said barrels.

4. The process of pitching barrels and the like, which consists in supplying them with an interior coating of melted pitch, removing the heated gaseous contents of the barrels, continuously admitting air to the interior of the barrels and continuously removing this air.

5. The process of pitching barrels and the like, which consists in supplying them with an inner coating of melted pitch and then reducing the pressure within the barrel below atmospheric pressure.

In testimony whereof I hereunto affix my signature in the presence of two witnesses.

JOHN H. G. ZUNNER.
